GRILLE GUARD FOR MOTOR VEHICLES

Filed June 28, 1947

FIG. 1.

FIG. 2.

LEO BUSTIN,

INVENTOR.

BY: Julian J. Wittel,

HIS ATTORNEY.

UNITED STATES PATENT OFFICE

152,059

DESIGN FOR A GRILLE GUARD FOR MOTOR VEHICLES

Leo Bustin, New York, N. Y.

Application June 28, 1947, Serial No. 139,995

Term of patent 3½ years

(Cl. D14—6)

To all whom it may concern:

Be it known that I, Leo Bustin, a citizen of the United States, residing at New York city, in the county of New York and State of New York, have invented a new, original, and ornamental Design for a Grille Guard For Motor Vehicles, of which the following is a specification, reference being had to the accompanying drawings, forming a part thereof.

In the drawings:

Fig. 1 is a front view of a grille guard for motor vehicles, showing my new design.

Fig. 2 is a top or plan view thereof.

I claim:

The ornamental design for a grille guard for motor vehicles, as shown.

LEO BUSTIN.
